UNITED STATES PATENT OFFICE.

CHARLES LAPORTE AND IVAN ORNBERG, OF DETROIT, MICHIGAN, ASSIGNEES TO HUPP MOTOR CAR CORPORATION, OF RICHMOND, VIRGINIA, A CORPORATION OF VIRGINIA.

COMBINED OIL-PUMP AND IGNITION-DISTRIBUTER MOUNTING.

1,287,351.

Specification of Letters Patent.

Patented Dec. 10, 1918.

Application filed December 14, 1917. Serial No. 207,027.

To all whom it may concern:

Be it known that we, CHARLES LAPORTE and IVAN ORNBERG, both citizens of the United States of America, residing at Detroit, in the county of Wayne and State of Michigan, have invented certain new and useful Improvements in Combined Oil-Pumps and Ignition-Distributer Mountings, of which the following is a specification, reference being had therein to the accompanying drawings.

The invention relates to engines and has particular reference to the construction of the ignition distributor and oil pump. It is the object of the invention to provide a combined unit which may be readily mounted on or detached from the engine housing, and to this end comprises the construction as hereinafter set forth.

20 In the drawings:

Figure 1 is a sectional end elevation.

Fig. 2 is an elevation at right angles to Fig. 1.

A is the engine casing having an extension 25 at one end thereof forming the ledge B, and C is a driven shaft within the housing having mounted on its end portion a gear D preferably of a spiral type. Our improved unit is mounted upon the ledge B and is 30 driven from the gear D. Specifically the construction comprises a casing E for the pump, which as shown is of the gear type. The driving shaft F for the pump extends 35 vertically and is provided at its lower end with a spiral gear G for engaging with the gear D, the former being insertible through an aperture H in the ledge B. Adjacent to the gear G is a bearing I, which is formed on a lower section J of the casing E, the bearing I being also insertible through the aperture H and having a portion I' for fitting 40 said aperture and positioning the gear. K and K' are the intermeshing gears of the pump arranged in a recess in the casing E. 45 The shaft F passes through the casing E and extends upward thereabove, the upward extension being housed in a tube L which is secured to a boss M on the housing E by means of a set screw N. At the upper end 50 of the tube L is a casing O for the distributor (not shown) which is driven from the extension of the shaft F.

With the construction as described, the housing E may be secured in position by 55 suitable means, such as the bolts P, and when

thus secured will hold the shaft F and spiral gear G in proper positions for the meshing of the latter with the driving gear D. In operation, the oil which is propelled by the pump is delivered through suitable channels 60 in the casing, such as Q and any leakage around the shaft through the bearings into the tube L is permitted to drain back into the crank case through the channel R.

What we claim as our invention is:

1. The combination with an engine casing, a driven shaft in said casing and a gear-wheel thereon, of a combined pump and ignition timer unit mounted outside of said casing and provided with a drive-shaft 70 and gear mounted thereon and projecting through an aperture in said casing into engagement with the gear therein.

2. In an engine, the combination with the casing having a projecting portion forming 75 a ledge and a driven shaft and gear thereon within said portion, of a combined pump and ignition timer unit seated upon and secured to the ledge of said casing, said unit having a downwardly projecting portion 80 with a shaft extending therethrough, and a gear-wheel on said shaft, said gear-wheel and downwardly-extending portion being insertible through an aperture in the ledge of said casing into engagement with the 85 wheel within the case.

3. In an engine, the combination with a casing having a projecting portion forming a horizontal ledge and a driven shaft within said portion having a gear-wheel mounted 90 thereon, of a combined pump and ignition timer unit mounted on said ledge, said unit comprising a pump casing, a shaft extending vertically therethrough and projecting upward and downward therefrom, a tubular housing for the portion of said shaft above said casing having an enlargement at its upper end for an ignition timer driven by said shaft, a downwardly-projecting portion on said casing forming a bearing for 100 the downward extension of the shaft and having a portion fitting an aperture in the ledge of said casing, and a gear-wheel at the lower end of said shaft insertible through said aperture in the casing and positioned 105 to mesh with the first-mentioned gear-wheel within said casing.

4. In an engine, the combination with a casing having a projecting portion forming a horizontal ledge and a driven shaft 110

- in said casing with a gear-wheel mounted thereon, of a combined pump and ignition timer unit mounted on the ledge of said casing comprising a housing for the pump, 5 a tubular housing connected thereto and extending upward therefrom, a housing for the timer at the upper end of said tubular housing, a shaft extending vertically through said housings forming a driver for the pump and timer, the lower end of said shaft projecting downward and having a gear-wheel mounted thereon, said gear-wheel and downwardly-projecting portion of the shaft being insertible through an aperture 10 in the ledge of said casing and into operative relation with the first-mentioned gear-wheel within the casing, and means for detachably securing said unit to said ledge.
5. In an engine, the combination with the casing having a hollow projection portion and a driven shaft and gear thereon within said portion, of a combined pump and ignition timer unit seated upon and secured to the projecting portion of the casing, said unit having a part extending into said pro- 15
- jecting portion of the casing with a shaft mounted in said part and a gear mounted thereon, the last-mentioned gear and said part of the unit being insertible through an aperture in the projecting portion of the casing into engagement with the gear within said portion. 30
6. In an engine, the combination with a casing having a projecting portion forming a ledge, of a combined pump and ignition timer unit seated upon and secured to the ledge of said casing, said unit having a downwardly-projecting portion with a shaft extending therethrough carrying a driving member, said driving member and downwardly-extending portion being insertible through an aperture in the ledge of the casing and means within the projecting portion of the casing for actuating said driving member. 35

In testimony whereof we affix our signatures.

CHARLES LAPORTE.
IVAN ORNBERG.
